CLAIM

The ornamental design for a spa step, as shown and described.

DESCRIPTION

FIG. 1 is a top-front-left perspective view of a spa step showing my new design according to a first embodiment; FIG. 2 is a front elevational view thereof; FIG. 3 is a rear elevational view thereof; FIG. 4 is a left side elevational view thereof, the right side elevational view being the mirror image thereof; FIG. 5 is a top plan view thereof; FIG. 6 is a bottom plan view thereof; FIG. 7 is a top-front-left perspective view of a spa step showing my new design according to a second embodiment; FIG. 8 is a front elevational view thereof; FIG. 9 is a left side elevational view thereof, the right side elevational view being the mirror image thereof; FIG. 10 is a bottom plan view thereof; FIG. 11 is a top-front-left perspective view of a spa step showing my new design according to a third embodiment; and, FIG. 12 is a top plan view thereof.

The broken lines shown in the drawings depict portions of the spa step that form no part of the claimed design.

1 Claim, 12 Drawing Sheets
